UNITED STATES PATENT OFFICE.

ARTHUR K. MITCHELL, OF BRONXVILLE, NEW YORK, ASSIGNOR TO ST. JOSEPH LEAD COMPANY, OF NEW YORK, N. Y., A CORPORATION OF NEW YORK.

DIPPER MOUNTING.

Application filed November 3, 1921. Serial No. 512,413.

To all whom it may concern:

Be it known that I, ARTHUR K. MITCHELL, a citizen of the United States, and resident of Bronxville, county of Westchester, and 5 State of New York, have invented certain new and useful Improvements in Dipper Mountings, of which the following is a specification.

This invention relates to an improved 10 dipper mounting for shoveling or excavating machines and generically considered, has for its primary object and purpose to provide a dipper mounting designed for use in connection with shoveling machines such 15 as are employed in underground mining whereby the filling of the dipper with the ore is facilitated in the forward thrust movement of the dipper and liability of breaking the boom operating connections or 20 other parts is reduced to a minimum.

In carrying out my present invention, in one embodiment thereof, I propose to mount the dipper on a swinging and traveling boom by suitable means which permits 25 of a yieldingly resisted longitudinal movement with a simultaneous transverse oscillation of the dipper in its forward thrust. This produces the equivalent of a worming 30 action so that the dipper teeth will readily bite into the pile of ore, facilitating the collection of the ore within the dipper and relieving the dipper teeth of excessive strains.

It is a further object of the invention to 35 provide an improved dipper mounting as above characterized which is of simple construction, of maximum stability, reliable and efficient for the purpose in view and adaptable for use in connection with various 40 forms of dippers or shovels.

With the above and other objects in view, the invention consists in the improved dipper mounting to be hereinafter more particularly described and in the form, construction and arrangement of the several 45 parts illustrated in the accompanying drawings and subsequently incorporated in the subjoined claims.

In the drawings wherein I have illustrated 50 one practical and satisfactory embodiment of the invention and in which similar reference characters designate corresponding parts throughout the several views:

Figure 1 is a top plan view showing the

forward ends of the boom arms and the connecting head therebetween with the dipper or shovel mounted upon said head;

Figure 2 is a central longitudinal section taken on the line 2-2 of Figure 1;

Figure 3 is a section taken on the line 3-3 of Figure 1; and

Figure 4 is a front end elevation illustrating in dotted lines the transverse swinging movement of the dipper.

The invention constituting the subject matter of the present application is particularly designed for use in connection with an underground mining machine of the type disclosed in my Patent 1,501,795, 70 issued July 15, 1924, though it is to be understood that in so far as my present disclosures are concerned, they are not necessarily limited in their utility to application and use in connection with such a machine 75 but can be employed generally upon mining or excavating machines of the various types now in general use.

In the machine of my patent above referred to, a pair of longitudinally traveling, vertically swinging boom arms are supported upon a turn table. In the accompanying drawings, the forward ends of the boom arms 5 are rigidly connected to each other by means of a head 6. The means 80 whereby this head is connected to the boom arms constitutes no essential part of the present invention, but it may be stated that in the end of each of the arms 5 a member 7 is inserted and securely welded to the arm. Each of these members has a forwardly extending tapering portion 8. The head 6 comprises a central portion 9 from opposite sides of which tubular arms extend at an oblique inclination and in a rearward direction, each of the arms terminating in a hub 10 having a tapering bore to receive the part 8 of one of the members 7. The parts 8 and 10 are suitably keyed together and the members 7 terminate at their forward ends in threaded extensions to receive the nuts 11 which are adjusted into tight bearing contact against the hubs 10 and are then pinned or otherwise fixed in their adjusted positions.

The center portion 9 of the boom head is provided with a longitudinally extending chamber 12 closed at its rear end and opening at its other end through the front side of the head. The dipper or shovel 105

13 is suspended from the boom head but instead of rigidly fixing this dipper in position, it is mounted for a bodily longitudinal movement as well as a transverse oscillating movement with respect to the boom head. The specific form or construction of the dipper is not of importance, though I preferably use a dipper which is similar in many respects to that disclosed 10 in Patent 1,418,321, issued June 6, 1922. For the purpose of the present explanation it will suffice to state that the rear wall of the dipper 13 is provided with a part 14 extending upwardly above the upper edges of the side walls of the dipper and positioned at the rear side of the chambered central part 9 of the boom head.

Within the outer end of the chamber 12 a piston 15 is snugly fitted for reciprocating movement, said piston having a stem or rod 16 of reduced diameter which is loosely engaged through an opening 17 in the rear wall of said chamber. The end portion of the piston stem is again reduced in diameter 25 and projects rearwardly through an opening 18 in the upward extension 14 on the rear wall of the dipper. A nut 20 threaded upon the end of the piston stem tightly clamps the extension 14 against the shoulder 30 formed by the inner end of the reduced portion of the piston stem 16 and is pinned or otherwise securely locked against rotation. Within the chamber 12 of the boom head and surrounding the piston head 16 a coil 35 spring 19 is arranged and bears at its forward end against the piston 15 and at its rear end against the wall of said chamber. The outer end of the piston 15 forwardly of the boom head is formed with a transversely extending bail bar 20^a, the ends of which are downwardly turned and riveted to the opposite side walls of the dipper body as at 20'. These side walls adjacent to the rear wall of the dipper are provided 40 in their upper edges with the concave recesses 21 which accommodate the tubular portions of the boom head in the transverse rocking or oscillating motion of the dipper. It will thus be seen that the dipper is rigidly 45 connected to the front and rear ends of the piston and that the dipper is normally held yieldingly in a forwardly projected position with relation to the boom head by means of the spring 19. I also preferably 50 provide means for yieldingly resisting a transverse rocking or oscillating movement of the piston and the dipper with respect to the boom head. As herein shown, this 55 means may consist of a leaf spring 22 having one or more laminations, the medial portion of this spring being securely fixed upon the forward end of the medial portion 9 of the boom head and the ends of the spring bearing upon the bail bar 20^a at opposite 60 sides of the piston. However, this arrange-

ment of the spring 22 is merely suggestive and various other alternatives for yieldingly resisting the transverse oscillation of the dipper might be adopted.

Having now described the illustrated embodiment of my improved dipper mounting, its operation will be understood as follows:

In the forward travel of the boom in its lowered position, as the dipper is thrust into the pile of ore or other material, upon encountering an appreciable resistance to such thrusting movement, the dipper will move longitudinally and rearwardly with respect to the boom head and the spring 19 will be placed under compression and will yieldingly limit such movement. Should the dipper teeth on one side of the center of the dipper encounter a large mass of ore, the dipper will rock or tilt transversely as shown in dotted lines in Figure 4, against the action of the spring 22 or other yieldable resistance so that the teeth will be positioned below the ore mass. This rocking or oscillating movement together with the yielding rearward movement of the dipper produces the equivalent of a worming action as in the manual use of a shovel and greatly facilitates the gathering or collection of the ore into the dipper. Also the possibility of the dipper being broken off, mutilated or distorted, is substantially obviated reducing the necessity for repairs and the expense incident thereto to a minimum. It is of course understood that upon overcoming the momentary resistance to the forward thrust of the dipper into the mass of the ore, the spring 19 immediately acts to again project the dipper forwardly upon the boom head to its normal position. This spring may thus function repeatedly during each thrusting movement of the dipper. As the said spring is entirely housed within the chamber 12, the ore or other material cannot come into contact therewith and interfere with the proper performance of its functions.

From the foregoing description considered in connection with the accompanying drawings, the construction, manner of operation and several advantages of my improved dipper mounting will be clearly and fully understood. The invention as herein disclosed is simple and compact in its arrangement, reliable and efficient in operation and will not add materially to the production cost of mining or excavating machines as shown in my prior application or heretofore in general use.

While I have herein shown and described one satisfactory and practical embodiment of the invention, it is nevertheless to be understood that the improved dipper mounting might also be exemplified in numerous other alternative constructions and I accordingly reserve the privilege of adopting

all such legitimate changes as may be fairly embodied within the spirit and scope of the invention as claimed.

I claim:

- 5 1. In combination with a boom, a dipper, and means for mounting said dipper upon the boom for limited longitudinal movement and for transverse oscillation with respect to the boom in the forward thrust of the dipper.
- 10 2. In combination with a boom, a dipper, means for mounting the said dipper upon the boom for limited longitudinal movement and transverse oscillation with respect thereto in the forward thrust of the dipper, and means resisting such movements relative to the boom and acting to yieldingly hold said dipper in its normal position.
- 15 3. The combination with a boom having a chambered head, a piston working in said chamber, a dipper suspended from said piston beneath the boom head, and a spring arranged in said chamber coacting with the piston to yieldingly resist rearward movement of the dipper and piston relative to the boom head in the forward loading thrust of the dipper.
- 20 4. In combination with a boom, a dipper, means supporting the dipper from the boom and permitting of a transverse oscillating movement of the dipper with respect to the boom in the forward thrust of the dipper, and means mounted on the boom and coacting with said supporting means to resist such oscillation of the dipper and for yieldingly holding the same in a normal position with relation to the boom.
- 25 5. In combination with a boom, a dipper, a piston mounted upon the boom to reciprocate longitudinally thereof and fixed at its opposite ends to the dipper, and a spring

coacting with the piston to project the dipper forwardly of the boom and yieldingly hold said dipper in a normal position.

6. In combination with a boom, a dipper, a piston fixed to the dipper and mounted upon the boom for reciprocation longitudinally thereof and for axial oscillation, a spring coacting with the piston to yieldingly resist a rearward longitudinal movement of the dipper and piston in the forward thrust of the dipper, and additional means for yieldingly resisting the oscillation of the dipper and the piston with respect to the boom.

7. In combination with a boom, having spaced arms and a head connecting said arms, a dipper, a piston mounted in said head for reciprocation longitudinally of the boom and fixed at its opposite ends to the dipper, and a spring mounted in the boom head and coacting with the piston to yieldingly resist the rearward movement of the dipper and the piston in the forward thrust of the dipper.

8. In combination with a boom having spaced arms and a head connecting the same, said head having a chamber, a dipper, a piston mounted to reciprocate and oscillate in said chamber and connected to the dipper, a spring arranged in said chamber coacting with the piston to yieldingly resist a rearward movement of the dipper and the piston in the forward thrust of the dipper and additional means yieldingly resisting the oscillating movement of the piston and the dipper with respect to the boom head.

In testimony that I claim the foregoing as my invention, I have signed my name 80 hereunder.

ARTHUR K. MITCHELL.
